Attorney

UNITED STATES PATENT OFFICE.

CHARLES E. MACY, OF IOWA HILL, CALIFORNIA.

AUTOMATICALLY-OPERATED ELECTRIC IRON.

Application filed March 3, 1925. Serial No. 12,939.

To all whom it may concern:

Be it known that I, CHARLES E. MACY, a citizen of the United States, residing at Iowa Hill, in the county of Placer and State of California, have invented certain new and useful Improvements in Automatically-Operated Electric Irons, of which the following is a specification, reference being had to the accompanying drawings.

This invention relates to electric irons, and particularly to means for controlling the circuit through the heating element of the electric iron.

In the ordinary electric iron there is great danger of leaving the circuit on after the iron is set aside and the operator forgetting that the circuit is on. Telltale lamps have been disposed in the circuit of the heating element so that when the lamp is on the operator, seeing it, may know that the current is still on and turn the switch to cut off the current. Thermostatic devices have also been provided to automatically cut off the circuit when the iron has reached a certain degree of heat.

The object of the invention is to provide an electric iron so constructed that the circuit through the heating element is closed either when the handle is gripped or when the iron is disposed upon a stand but that this circuit is broken when the grasp on the handle is released, unless the iron be placed upon the stand, thus eliminating all danger of fire caused by leaving the iron resting upon a combustible surface, and also eliminating damage due to overheating the iron.

A further object is to provide a device of this character in which there is a switch in the circuit including the heating element, this switch being connected to one of the sections of a sectional handle and being so arranged that when the handle is grasped the movable section will be drawn toward the fixed section, thus closing the circuit through the switch, and to provide a stand upon which the iron may rest, this stand having a member which engages the switch and forces the switch closed when the iron is placed in proper position upon the stand.

Other objects will appear in the course of the following description.

My invention is illustrated in the accompanying drawing, wherein:—

Figure 1 is a side elevation of an iron constructed in accordance with my invention,

the handle being partly broken away and the rear end of the iron being partly broken away;

Figure 2 is a top plan view of the stand upon which the iron rests;

Figure 3 is a fragmentary rear end elevation showing the normal position of the contact member when the iron is not upon the stand and not being grasped;

Figure 4 is a diagram showing the wiring for the parts.

Referring to the drawing, 10 designates an electric iron of any suitable or usual construction and having therein a heating element 11. This iron is provided with a handle section 12 carried by supports 13 and 18. One of these supports is shown as connected to a socket 14 within which an electric light cord 15 is disposed, the wires of this electric light cord 15^a and 15^b extending down into the casing of the iron, and one of these wires is connected to the heating element in the usual manner.

Disposed within the rear end of the iron is a longitudinally shiftable switch member 16 which also carries a conductor 16^a and is provided with a shoulder 17. This switch member 16 projects out through a longitudinally extending passage in the rear end of the iron and projects into a recess 18 formed in the rear end of the iron so that while the rear end of the contact member 16 projects beyond the bottom of the recess, it does not project beyond the general plane of the rear face 19 of the iron. The opposite end of the switch member 16 is opposed to a contact point 20 and when the switch member is forced inward it will have electrical engagement with this contact point. Normally, however, the switch member is urged away from the contact point 20 by means of the coiled spring 21 which bears against the shoulder 17.

The handle section 12 is crescent-shaped in cross section, and disposed within the longitudinal recess defined by the crescent-shaped handle section 12 is a handle section 22. This is mounted upon a slightly curved arm 23 whose lower extremity is forced, as at 24, to embrace the switch member 16 and bear against the shoulder 17. Opposite the rear end of the section 22 there is provided a fulcrum. In other words, the upper end of the arm 23 is hinged at this point to ears 25 projecting from the support 13^a so that

when the handle section 22 is grasped and drawn upward against the fixed section 12 the handle section rocks upon the fulcrum formed by the ears 25 and the lower end of 5 the arm 23 is shifted against the shoulder 17 and forces the switch 16 against the contact member 20, thus completing the circuit through the heating element.

Thus it will be seen that whenever the 10 iron is grasped for operation the circuit is completed and the heating element energized, but that as soon as the grasp upon the handle of the iron is released the spring 21 will urge the switch away from the contact 15 point and the current to the heating element will be cut off. It is, of course, necessary to provide means upon which the iron may rest, and to this end I provide a stand 26. This stand has for one of its essential elements 20 the downwardly and rearwardly extending supporting element 27, preferably carrying rollers 28 upon which the under surface of the iron directly rests so that the iron will by gravity tend to shift rearward. 25 At the rear end of the support 26 there is provided an upwardly extending flange 29 which is forwardly bowed, as shown in Figure 2, so as to provide a contact portion 30 adapted to engage with the switch 16 and force this switch inward to the depth of the 30 recess in the rear face of the iron, thus forcing the switch 16 against the contact point 20 and closing the circuit through the heating element. Thus so long as the iron is disposed upon the support 26 the heating element will be energized, and when the iron is picked up the grasp of the hand upon the handle will also hold the switch closed and the switch will remain closed while the 35 iron is being used, but when the iron is set down, unless it is disposed upon the stand 26, the current will be cut off of the heating element and the iron will shortly grow cool.

40 I claim:—

1. In an electric iron, a heating element, a switch controlling the passage of current to the heating element, a handle formed in two similar sections, one of said sections being rigidly connected to the iron, the lower of said sections being pivotally mounted at one end at a point adjacent to the like end of the other section and said pivoted section of the handle having an arm extending 45 downward into the body of the iron and operatively engaging said switch, and resilient means urging the switch to an open position and the movable section of the handle away from the fixed section thereof.

50 2. An electric iron including an electrically energized heating element, a switch controlling the passage of current thereto, means resiliently urging it to a position to break the circuit through the heating element, a handle for the iron, handle-operated

means for shifting the switch into position to close the circuit through the heating element, the switch having a portion extending out through the side wall of the iron and projecting beyond the face of the same, a 70 stand for the iron, and means on the stand engaging said projecting portion of the switch and shifting the switch inward whereby when the iron is disposed upon the stand the switch will be shifted into its circuit-closing position against the action of said spring.

3. In an electric iron, a heating element, a switch controlling the passage of current thereto, said switch being longitudinally 80 movable within the iron and projecting at the rear end of the iron, a spring urging the switch to its projected position and out of electrical engagement with the heating element, and a stand having means thereon to engage the rear end of the switch and shift it into electrical engagement with the heating element when the iron is disposed upon the stand.

4. In an electric iron, a heating element, a switch controlling the passage of current thereto, said switch being longitudinally movable within the iron and projecting at the rear end of the iron, a spring urging the switch to its projected position and out of electrical engagement with the heating element, a stand having a downwardly and rearwardly inclined supporting face, and means at the rear end of the stand adapted to engage said switch when the iron rests upon the stand and bears against said means to thereby force the switch into position to close the circuit through the heating element.

5. The combination with an electric iron, the rear end of the iron having a recess, a switch disposed within the iron and controlling the passage of current through the heating element of the iron, said switch projecting at its rear end into said recess, of a 105 support for the iron, said support being downwardly and rearwardly inclined and having rollers to support the iron, the rear end of the support having an upwardly and inwardly extending member adapted to engage with said switch and force the switch forward and into contact with the heating element when the iron moves rearward on the support under the action of gravity.

6. The combination with an electric iron 120 having an electric heating element, handle-operated means for closing a circuit through the heating element when the handle is grasped and in combination with a support for the iron having a member toward which the iron moves under the action of gravity, said member being adapted, when the iron is in place, to close the circuit through the heating element.

7. An electric iron including a heating 130

element, a longitudinally movable switch mounted in the rear end of the iron and adapted, when moved forward, to close a circuit through the heating element and when moved rearward to break the circuit, a spring urging said switch rearward, the end of the switch projecting beyond the rear end of the iron, a sectional handle, one of said sections being fixed and the other movable, the movable section having an arm operatively engaging the switch whereby when the handle is grasped and the sections are forced toward each other the switch will be shifted to a position to close the circuit through the heating element.

8. An electric iron comprising a body having handle supporting members, a handle section mounted between the supporting members, an electric cord having one of its wires connected to one of said supporting members, a longitudinally movable switch disposed in the rear end of the iron, a spring urging said switch rearward and the rear

end of the switch beyond the rear end of the iron, said switch when moved forward 25 against the action of the spring closing the circuit through the heating element, an arm carried by the movable section of the handle and engaging said switch, a fulcrum supporting the movable section and the arm 30 whereby when the movable section is forced toward the fixed section of the handle the arm will shift the switch to its circuit-closing position, and a support for the iron having rollers disposed in a downwardly and 35 rearwardly extending plane, the rear end of the support having an upwardly extending member adapted to engage the rear end of the switch and force it forward into electrical engagement with the heating element 40 when the iron moves rearward under the action of gravity on said support.

In testimony whereof I hereunto affix my signature.

CHARLES E. MACY.
